TRESTLE BOAT-DAVIT OF THE ROTATION
AND GRAVITY TYPE

Domenico Barricelli, Genoa, Italy

Application June 30, 1949, Serial No. 102,251
In Italy August 12, 1948

6 Claims. (Cl. 9—39)

1

The present invention relates to boat lowering gear and is particularly directed to a davit, preferably used in pairs, and serving to support a boat, for example, a life boat, in an inboard position and movable to an outboard position to permit the boat to be launched either manually or by the operation of a winch or other mechanism.

An object of the present invention is to provide an improved boat davit of the kind pivotally mounted at its lower end for swinging movement between inboard and outboard positions which is simple in construction and movement, relatively light in weight, and certain and reliable in its launching operation even when the ship on which the davit is mounted is listing severely or on its beam ends.

Another object is to provide a boat davit of the described character which is constructed so that the weight of the supported boat is employed in effecting initial swinging movement of the davit to its outboard or launching position.

Still another object is to provide a boat davit of the described character which is constructed and arranged so that the space around the davit is relatively unobstructed thus making it possible to locate the davit at any point at the side of the deck without interfering with free passage or use of the adjacent deck space.

A further object of the present invention is to provide a self contained boat lowering gear having the described characteristics so that the gear may be mounted as a unit in place of existing devices without requiring excessive alteration of the ship structure.

In accordance with the present invention, the above, and other objects, features and advantages, are accomplished by providing a boat davit which includes an outwardly curving beam pivotally mounted at its lower end adjacent the side of the deck for swinging in a vertical plane. A triangular trestle or strut is pivotally mounted at its base for swinging about an axis disposed outboard and parallel relative to the axis of swinging of the davit beam. The triangular trestle, at its apex, pivotally supports a guide block which is permanently connected to the davit beam for sliding along the latter and engageable with spaced stops on the beam for limiting the inboard and outboard positions of the latter. A single fall or rope is provided for the dual function of controlling the position of the trestle or strut relative to the davit beam and hence the position of the latter, and for hoisting and lowering the boat supported from the free end of the davit beam. Further, the boat davit embodying

5

the invention includes a lever member formed with two angularly related arms and pivotally mounted at the junction of such arms on the swinging axis of the davit beam.

One arm is formed to engage under the supported boat in its

inboard position while the other arm engages against the davit beam in the outboard direction

to urge the beam outwardly in response to the weight of the boat on the first mentioned arm.

These and other objects, features and advantages of the present invention will be apparent in the following description of preferred embodiments which is to be read in connection with the accompanying drawing forming a part hereof, and wherein:

Fig. 1 is a diagrammatic side elevational view of a boat davit embodying the present invention and shown in its inboard position;

Fig. 2 is a front elevational view of a triangular trestle or strut forming a part of the boat davit of Fig. 1;

Fig. 3 is a fragmentary sectional view along the line 3—3 of Fig. 1 and showing the structure for slidably connecting the trestle of Fig. 2 to the davit beam;

Fig. 4 is a diagrammatic side elevational view similar to Fig. 1, but showing the davit in an intermediate outboard position; and

Fig. 5 is a diagrammatic side elevational view similar to Figs. 1 and 4, but showing the davit in its fully extended outboard position with the lowering of the boat having been commenced.

Referring to the drawing in detail, and initially to Figs. 1, 4 and 5 thereof, a boat davit embodying the present invention is there shown to include a davit beam 1 pivotally mounted at its lower end for swinging in a vertical plane about an axis 2 disposed close to the supporting deck and at a suitable distance from the rim of the latter. At least the upper portion of the davit beam is curved or bent in the outboard direction so that a boat 13 supported by a fall 10 suspended from the upper end of the beam 1 will clear the lower portion of the davit beam even when the latter is in its extreme inboard position (Fig. 1). A trestle or strut 4 of triangular shape (Fig. 2) is pivotally mounted at its base for swinging about an axis 5 disposed parallel and outboard relative to the axis 2 about which the davit beam swings. A slide member 3 is pivotally mounted on a pivot pin or axle 21 at the apex of the triangular trestle 4 and slidably engages the beam 1 for movement along the latter. As seen in Fig. 3, the beam 1 is preferably formed with a flange extending along at least its out-

board edge, and the slide member 3 is of substantially C-shaped cross-section with inturned flanges 22 engaging in back of the beam flange to prevent separation of the slide member from the davit beam. Thus, the rotational or swinging movements of the beam 1 and trestle 4 are interdependent and, as the trestle swings in the outboard direction, the slide member 3 travels upwardly on the beam 1 and the latter also swings in the outboard direction.

In order to define the inboard and outboard limits of the swinging of davit beam 1, spaced limits of the stops or abutments 6 and 7 are fixed on the beam stops or abutments 6 and 7 are fixed on the beam 1 in the path of movement of the slide member 3. As seen in Fig. 1, the stop 6, disposed below slide member 3, is engaged by the latter when the beam 1 is in its extreme inboard position and prevents further downward movement of the member 3 and hence further inward swinging of the davit beam. As seen in Fig. 5, the stop 7, disposed above the slide member, is engaged by the latter when the beam is in its extreme outboard position and prevents further movement of the member 3 toward the top of the beam and hence further outward swinging of the davit beam.

The fall 10 is connected at one end to the upper or free end of the davit beam 1 and passes through a sheave block from which the boat 13 is suspended. The fall 10 continues from the sheave block and passes over a fair lead or pulley 11 rotatably mounted adjacent the free end of the beam 1. From the fair lead 11, the fall 10 extends along the curved length of the beam 1 and is guided by fair leads 16 and 17 which are rotatably mounted on the beam 1 at points on the latter adjacent the center and immediately below the stop 6, respectively. A pulley 18 is rotatably mounted on the trestle 4 adjacent the apex or upper end of the latter so that, as the beam 1 swings in the outboard direction, the distances between the axes of the pulleys or fair leads 17 and 18 and between the axis of pulley 18 and axis 2, about which the beam 1 swings, are respectively lengthened. The fall 10 passes around and under the fair lead 17 and thence over and around the pulley 18 on the trestle 4. Finally, a pulley or fair lead 19 is mounted for rotation about the axis 2 close to the deck, about which the beam swings, and the fall 10 is led from the pulley 18 under the pulley 19, as at 20, and thence to a device (not shown) for reeling in or paying out the fall line, which device may be a manual or powered winch or other suitable mechanism mounted on the beam 1 itself or on adjacent structure. At this point it should be noted that the combined resistance to turning of the pulleys or fair leads 11, 16 and 17 and of the sheave block from which the boat 13 is suspended is preferably greater than the frictional resistance to sliding movement of the member 3 along the beam 1 for a purpose that will appear hereinafter in the description of the operation of the boat davit embodying the invention.

The boat davit further includes a lever member having two angularly related integral arms 8 and 9 which is rockably mounted at the junction of its arms for turning about the axis 2. The arm 8, at its outboard or free end is formed to bear the keel 12 of the supported boat 13, and the arm 9, at its free end, is formed to press against the beam 1 in the outboard direction to urge the davit beam to swing outwardly in response to the weight of the boat upon the arm 8. Thus, when the fall or line 10 is released with the boat supported as in Fig. 1, the weight of

the boat on the arm 8 will cause the latter to rock in the clockwise direction, as viewed in Fig. 1, and the arm 9, formed integral with the arm 8, will urge the beam 1 in the outboard direction to initiate swinging of the davit beam to its outboard or launching position. This action of the lever member formed by the arms 8 and 9 ensures proper functioning of the described boat davit even when the ship, on which the latter is mounted, is keeled over in the direction away from the edge of the deck adjacent the davit.

Since the davit beam 1 curves or is bent in the outboard direction, it is apparent that the weight of the boat, substantially centered on a vertical line extending through the free or upper end of beam 1, will produce a turning moment about the axis 2 even after the keel 12 of the boat has been released from contact with the arm 8. This turning moment will cause the beam 1 to swing in the outboard direction and such swinging of the beam will be communicated to the trestle 4 to effect movement of the slide member 3 upwardly along the beam and extension of the distance between the axes of the pulleys 17 and 18 and of the pulleys 18 and 19. Since the combined resistance to turning of the pulleys 11, 16 and 17 and of the sheave block supporting the boat is greater than the frictional resistance to sliding of the member 3, the payed out fall or line 10 is initially taken up in the lengthened passes of the fall or line between the pulley 18 and the pulleys 17 and 19, and therefore the boat substantially retains its initial position, with respect to the upper end of the davit beam, during the initial outboard swinging of the davit beam, as shown in Fig. 4. When the davit beam reaches its extreme outboard position, as determined by engagement of the slide member 3 against the upper stop 7 (Fig. 5), the payed out line can no longer be taken up by extension of the distances between the axis of the pulley 18 and the axes of the pulleys 17 and 19, and the weight of the boat cannot effect any further outward swinging of the davit beam so that such weight is then wholly operative to lower the sheave block relative to the upper or free end of the davit beam with the payed out fall line 10 running over the pulleys 11, 16, 17, 18 and 19 and through the sheave block. Thus, the boat 13 is lowered to the water and launched.

In raising the boat from the water, the beam 1 is initially in its fully extended or extreme outboard position (Fig. 5) and the sheave block is lowered for attachment to the boat. As the line 10 is reeled in, the sheave block is raised and the weight of the boat, causing a turning moment about the axis 2 in the clockwise direction as viewed in Fig. 5, retains the davit beam in its extreme outboard position so that the boat clears the side of the ship. Only after the sheave block has been fully raised and further movement thereof toward the pulley 11 is impossible, will reeling in of the fall or line 10 cause swinging of the davit beam in the inboard direction. Such inboard swinging is caused by the pull exerted on pulley 18 by the line 10 which reduces the distances between the axis of the pulley 18 and the axes of the pulleys 17 and 19 and thereby swings the trestle 4 inwardly to effect movement of the slide member 3 upwardly along the davit beam 1 with the resultant inward swinging of the davit beam. As the concluding phase of the inward swinging of the davit beam is completed, the arm 8 is rocked upwardly by the beam, acting against the arm 9 to engage under the keel 12 of the boat

so that the davit and boat are again in their relative positions shown in Fig. 1.

From the foregoing description it is apparent that the present invention provides a boat davit in which the beam 1 may be of relatively light construction by reason of the fact that the slide member 3 progresses toward the free end of the beam as the latter swings in the outboard direction and the trestle 4 acts as a jury strut and serves to support the beam 1 so that the bending stresses in the latter do not become excessive. Further, the triangular configuration of the trestle 4 provides lateral support for the davit beam thereby reducing lateral loads on the latter even when the vessel is pitching severely. It should also be noted that the fall or line 10 leaves the davit, as at 20, closely adjacent to the deck so that it does not interfere with the movements of crew or passengers in the area of the davits during the launching of the boats, and that the lever member comprised of the integral arms 8 and 9 ensures the movement of the davit to its launching or outboard position even when the vessel is on its beam ends or listing severely.

Having described a preferred embodiment of the invention by way of illustration, it is to be understood that the invention is not limited to this precise embodiment, and that changes and modifications, obvious to one skilled in the art, may be effected therein without departing from the scope of the invention as defined in the appended claims.

I claim:

1. A boat davit comprising first horizontal pivot means mounted adjacent the side of a ship's deck, second pivot means disposed inboard relative to said first pivot means and having an axis parallel to the latter, a supporting beam pivotally mounted at its lower end on said second pivot means for swinging in a vertical plane, said beam being longitudinally bent in the outboard direction so that the free end thereof is adapted to lie in the longitudinal medial plane of a boat supported in the davit when said beam is in an inboard position, a triangular trestle mounted at its base on said first pivot means, means pivotally mounted on the apex of said trestle and movable along said beam, said last mentioned means being permanently connected to said beam so that the swinging movements of said beam and said trestle about the respective pivot means are interdependent, spaced apart stop means on said beam in the path of said movable means and engageable with said movable means for limiting the swinging movements of said beam in both the inboard and outboard directions, lever means constructed and rockably mounted for engagement under the supported boat in the rest position of the latter and engageable with said supporting beam to induce initial swinging of said beam in the out-board direction in response to the weight of the boat bearing on the lever means, and rope and pulley means operatively connected to said trestle and beam for supporting a boat from the free end of the latter and for controlling the position of said trestle relative to said beam.

2. A boat davit as set forth in claim 1, wherein said lever means inducing the initial swinging of said beam in the out-board direction includes a lever member formed with two angularly related arms pivotally mounted at their junction on said second pivot means, the free end of the arm extending in the out-board direction being formed to bear the keel of the supported boat and

to resist lateral movement of the boat toward said beam, the other arm of said lever member having its free end formed to press against said beam in the out-board direction to urge said beam in that direction in response to the weight of the boat upon the first mentioned arm and so that rotation of said beam and trestle in the out-board direction may continue even after the swinging of said first mentioned arm has been arrested.

3. A boat davit as set forth in claim 1, wherein said rope and pulley means includes a first pulley rotatably mounted on said beam adjacent said free end of the latter, a second pulley rotatable on said beam at a predetermined distance inboard from said first pulley, a third pulley rotatable on said beam adjacent the pivoted end thereof, a fourth pulley rotatable on said trestle adjacent the apex of the latter, a fifth pulley rotatable about said second pivot means, and an elongated flexible rope member fixed at one end to said free end of the beam and then passing successively around the support pulley of the supported boat, said first, second, third, fourth and fifth pulleys so that said rope member leaves the davit adjacent the deck.

4. A boat davit as set forth in claim 3, wherein said pulleys are provided with an aggregate resistance to turning which is greater than the resistance to movement of said means movable along said beam so that relaxation of the tension of said rope member will initially cause out-board swinging of said beam and then lowering of the supported boat.

5. A boat davit comprising, in combination, an up-standing davit beam bent longitudinally in the outboard direction, means for mounting the lower end of said beam adjacent a ship's deck for pivoting movement in a vertical plane between inboard and outboard positions, a substantially triangular trestle having its base end pivoted adjacent the deck for swinging about an axis which is outboard of and parallel to the pivoting axis of said beam, a slide-block pivotally connected to the apex of said triangular trestle and having a sliding connection with said beam throughout the movement thereof, and a lever having two angularly related arms and pivotally mounted at the junction of said arms coaxially with said beam, the free end of one of said arms having means extending therefrom to contact the inboard side of said beam, the outer end of the other of said arms having means thereon for supporting the keel of a boat, the angle between said two arms being such that, when the davit beam is in the inboard position, the weight of a boat bearing upon the outer end of said other arm will cause said means extending from said one arm to bear against the inboard side of said beam and initiate rotation of said beam to the outboard position.

6. A boat davit comprising a davit beam pivotally mounted at one end adjacent the side of a ship's deck for swinging in a vertical plane between inboard and outboard positions, a trestle member pivotally mounted at one end for swinging about an axis which is outboard of and parallel to the swinging axis of said beam, means movable along said beam and connecting the other end of said trestle member to said beam, fall and pulley means operatively connected to said trestle member and beam for supporting a boat from the free end of the latter and for controlling the position of said trestle

member relative to said beam, and a lever member having two angularly related arms and pivotally mounted at the junction of said arms for rocking about the swinging axis of said beam, the free end of one of said arms being formed to bear the keel of a supported boat when said beam is in said inboard position, the free end of the other of said arms being formed to press against said beam in the outboard direction in response to the weight of the boat upon said one arm to thereby initiate swinging of said beam in the outboard direction.

DOMENICO BARRICELLI.
